(57) **CLAIM**

I claim the ornamental design for the container handle extension, as shown and described.

DESCRIPTION

FIG. 1 is a perspective view of the container handle extension showing my new design;

FIG. 2 is a right-side elevation view thereof;

FIG. 3 is a front side elevation view thereof;

FIG. 4 is a left-side elevation view thereof;

FIG. 5 is a rear side elevation view thereof;

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
